UNITED STATES PATENT OFFICE.

WESLEY J. ARMSTRONG, OF BUFFALO, NEW YORK, ASSIGNOR TO MCKINNON DASH COMPANY, OF BUFFALO, NEW YORK.

FOLDING TABLE.

1,313,662.

Specification of Letters Patent.

Patented Aug. 19, 1919.

Application filed September 28, 1916. Serial No. 122,646.

To all whom it may concern:

Be it known that I, WESLEY J. ARMSTRONG, a citizen of the United States, residing at Buffalo, in the county of Erie and 5 State of New York, have invented a new and useful Improvement in Folding Tables, of which the following is a specification.

This invention relates to tables or other supports which are collapsible into a small 10 compact package which can readily be carried about by hand or in an automobile or other vehicle.

The objects of the invention are to provide a strong and rigid table of this kind 15 of improved and simplified construction which can be readily set up or collapsed.

In the accompanying drawings:

Figure 1 is a perspective view of a table embodying the invention, showing the parts 20 of the same set up in position for use.

Fig. 2 is a perspective view thereof, showing the upper portions of the table folded downwardly.

Fig. 3 is a side elevation thereof, showing the same when almost completely folded.

Briefly stated, in the embodiment of the invention shown in the drawings, the folding table comprises a lower portion and an upper portion which is supported from the 30 lower portion and which includes an upper deck or platform, the lower portion of the table being first set up and locked into its operative position independently of the upper portion of the table. The parts comprising the upper portion of the table are 35 mounted on the lower portion and are adapted to be set up into operative positions after the lower portion is set up.

The lower portion of the table may be 40 constructed in any suitable manner, that shown comprising two pivotally connected supporting members or legs A A' which, in the construction illustrated, consist of two substantially rectangular metal frames having side bars or rods *a* connected by top and bottom cross bars or rods *a'* and *a''*. The legs A A' are crossed and hinged together intermediate of their ends so that they may be swung into operative positions as shown 45 in Figs. 1 and 2 or into a collapsed position as indicated in Fig. 3. In order to hold the legs in their operative positions, the top cross bars thereof are connected by means of a suitable rigid connecting member 50 which, in the construction shown, consists

of a lower deck or plate B, which is preferably hinged at one end to one of the top cross bars, this hinged connection being preferably made by bending the metal at one end of the lower deck around the top 60 bar. At its opposite end, the lower deck or plate B is provided with means for releasably engaging the other of the two top cross bars *a'*, such, for example, as a downwardly extending flange *b* which is adapted to hook 65 over the cross bar, and with depending side flanges or portions *b'* which are cut away at *b''*. When the platform or deck B is placed into its operative position, as shown in Figs. 1 and 2, the top cross bar enters between 70 the end flange *b* and the ends of the side flanges *b'* so that the two legs A A' are held against movement in either direction relatively to each other.

The upper portion of the table comprises 75 a table top which is supported from the lower portion of the table by pivoted arms or extensions. In the construction shown, the upper deck or table top is preferably made in two sections D D', which are hinged 80 together at *d* in such a way as to permit the top to fold upwardly when in the position shown in Fig. 1 and to prevent the two parts thereof from folding downwardly. The table top is supported from the lower portion of the table by means of supporting arms or extensions E E' which are adapted 85 to fold relatively to the legs A A', so that the table can be collapsed into compact form. The supporting arms or extensions 90 E E' are preferably of inverted U-shape, each comprising two side bars *e* *e'* pivoted at one end at *e''* to one of the side bars *a* of the legs A A'. The side bars of each supporting arm are connected at their upper 95 ends by means of a cross bar *e''* to which the opposite ends of the table top are connected. The portion D of the table top is pivotally connected to the cross bar *e''* by any suitable means, for example by bending the end *d'* 100 of the table top around the cross bar. The opposite end of the table top is adapted to be removably connected with the cross bar of the opposite supporting arm E' in such a way as to hold the supporting arm and the 105 table top in operative relation to each other. For this purpose the end of the table top is turned over, forming a flange *d''* and the sides of the table top are provided with downwardly depending flanges *d'''* which 110

terminate at d^4 so as to form a space between the flanges d^3 and the flange d^2 into which the cross bar e^3 of the supporting arm E is adapted to enter.

- 5 The lower ends of the side bars e^1 of the supporting arms are provided with hooked portions F which are so formed as to engage the upper faces of the side bars a of the table legs when the supporting arms E E' are in 10 their operative positions and to act as stops to limit the upwardly swinging movement of the supporting arms when the parts of the table are in their operative positions. By limiting the movement of the arms E E' 15 at their lower ends by means of the hooks F , and at their upper ends by means of the table top, the parts of the table are held rigidly in operative positions. The hooks F are preferably so formed as to frictionally 20 or yieldingly grip the legs A of the lower portion of the table to yieldingly hold the supporting members E E' of the table in their upper positions, thus facilitating the placing of the parts of the table into the 25 positions which they occupy when ready for use.

In setting up the table, the legs A are first separated and the lower deck or connecting member is placed in position to lock 30 the legs against movement relatively to each other. The arms are then raised so that the hooks F engage the side bars of the table legs and the table top is placed into holding engagement with the arm E' . The table is 35 thus set up step by step and after each step the parts are held in the positions in which they are set, thus facilitating the placing of the parts of the table in position for use. When the table is to be folded, the steps are 40 carried out in the reverse order mentioned.

The table is preferably made entirely of metal, although other material may be used, thus making a strong and rigid table which can be folded into a compact mass. The table 45 is simple in construction and contains few parts, so that the table is inexpensive to manufacture.

I claim as my invention:

1. In a folding table, the combination of 50 legs adapted to be folded together, arms hinged to said legs, parts on said arms adapted to engage said legs to limit the movement of said arms relatively to said legs, and a metal table top having one end 55 thereof bent to form a socket in which one of said arms is pivotally secured and having the other end bent to form a hooked portion adapted to releasably engage another arm.
- 60 2. In a folding table, the combination of legs adapted to be folded together, arm portions comprising substantially U-shaped members having a transverse part and free ends which are pivoted to said legs, said 65 arm portions being adapted to form exten-

sions of said legs, and a table top having a part pivotally connected to the transverse part of one of said arms and having a hooked connection with the transverse part of the other arm.

3. In a folding table, the combination of 70 a pair of crossed legs which are hinged together and adapted to fold relatively to each other, hooked portions on said arms adapted to engage said legs to limit the movement 75 of said arms relatively to said legs, and a table top comprising two pivotally connected sections, one of said sections having a part bent to form a socket in which an arm is pivotally connected to said section and 80 the other section having an integral hooked portion adapted to releasably engage said other arm.

4. In a folding table, the combination of 85 a pair of crossed legs which are hinged together and adapted to fold relatively to each other, a member for connecting said legs to hold the same in operative position, arms hinged to said legs and adapted to fold relatively to said legs, means for limiting the 90 movement of said arms relatively to said legs, and a table top hinged at one end to one of said arms, the other end of said table top being adapted to be moved into locking engagement with the other of said arms. 95

5. In a folding table, the combination of 100 a pair of crossed legs which are hinged together and adapted to fold relatively to each other, a member for connecting said legs to hold the same in operative position, arms hinged to said legs and adapted to fold relatively to said legs, means for limiting the movement of said arms relatively to said legs, and a table top comprising two sections 105 hinged together, one of said sections being hinged to one of said arms and the other of said sections being adapted to be removably connected with the other arm, said two table sections being adapted to fold relatively to each other, to said first mentioned arm and 110 to said legs.

6. In a folding table, the combination of 115 a pair of crossed legs which are hinged together and adapted to fold relatively to each other, a lower platform movably connected to one of said legs and adapted to releasably engage the other leg, arms hinged to said legs and adapted to fold relatively to said legs, a table top hinged to one of said arms and adapted to be moved into locking engagement with the other arm, and hooked 120 extensions on said arms adapted to yieldingly grip said legs to hold said arms in extended positions independently of said top and to stop the movement of said arms in 125 one direction.

7. In a folding table, the combination of 130 legs adapted to be folded together, arm portions comprising substantially U-shaped members pivoted at their free ends to said

legs and adapted to form extensions thereof, parts on said arm portions which are adapted to engage said legs to limit the movement of said arms relatively to said legs, and a 5 table top connecting and resting on said arm portions.

8. In a folding table, the combination of legs adapted to be folded together, arm portions comprising substantially U-shaped 10 members pivoted at their free ends to said legs, said free ends being provided with

hooked portions adapted to engage said legs to yieldingly hold said arm portions in positions in which they form extensions of said legs, and a table adapted to connect and rest 15 on said arm portions.

Witness my hand, this 31st day of August, 1916.

WESLEY J. ARMSTRONG.
